Coplan & Aronoff LLP(57) CLAIM

What is claimed is the ornamental design for a basket, as shown and described.

DESCRIPTION

FIG. 1 is a perspective view of a basket showing a new design;

FIG. 2 is a right side view of the basket of FIG. 1;

FIG. 3 is a left side view of the basket of FIG. 1;

FIG. 4 is a rear view of the basket of FIG. 1;

FIG. 5 is a front view of the basket of FIG. 1;

FIG. 6 is a top view of the basket of FIG. 1; and,

FIG. 7 is a bottom view of the basket of FIG. 1.

The components of the display shown in broken lines illustrate portions of the basket form no part of the claimed design.
